(57) **CLAIM**

I claim the ornamental design for a light sensor, as shown and described.

DESCRIPTION

FIG. 1 is a front left perspective view of one embodiment of a light sensor of the present disclosure;

FIG. 2 is a front right perspective view of the light sensor of FIG. 1;

FIG. 3 is a front elevational view of the light sensor of FIG. 1;

FIG. 4 is a top plan view of the light sensor of FIG. 1;

FIG. 5 is a bottom plan view of the light sensor of FIG. 1;

FIG. 6 is a first side elevational view of the light sensor of FIG. 1;

FIG. 7 is a second side elevational view of the light sensor of FIG. 1;

FIG. 8 is a front left perspective view of another embodiment of the light sensor of the present disclosure;

FIG. 9 is a front right perspective view of the light sensor of FIG. 8;

FIG. 10 is a front elevational view of the light sensor of FIG. 8;

FIG. 11 is a top plan view of the light sensor of FIG. 8;

FIG. 12 is a bottom plan view of the light sensor of FIG. 8;

FIG. 13 is a first side elevational view of the light sensor of FIG. 8; and,

FIG. 14 is a second side elevational view of the light sensor of FIG. 8.

The broken line showing of structural features is included for the purpose of illustrating non-claimed subject matter and forms no part of the claimed design.
